UNITED STATES PATENT OFFICE

GUSTAV C. PEARSON, OF DENVER, COLORADO, ASSIGNOR TO GARDNER-DENVER COMPANY, OF DENVER, COLORADO, A CORPORATION OF DELAWARE

LUBRICATOR

Application filed February 16, 1929. Serial No. 340,388.

In connection with the use of fluid actuated tools, the employment of lubricators placed in the air lines of hose supplying motive fluid to the tools has been found 5 very satisfactory for maintaining the tools properly lubricated.

It has been the custom to some extent where a number of tools are supplied from a single line through a manifold or by 10 branches leading from the main line, to put a lubricator in the main line in advance of the branches for the purpose of lubricating all the tools. This, however, has not proven entirely satisfactory for the reason that the 15 different tools require different amounts of lubricant. Therefore one may be over-supplied or flooded and another may not receive sufficient oil.

It is the primary object of the present 20 invention to provide an air line lubricator for a plurality of tools, provision being made whereby each tool is independently supplied and the amount of lubricant thereto can be independently controlled.

25 The embodiment of the invention that is at present considered the preferable one, is illustrated in the accompanying drawings, wherein:

Figure 1 is a plan view of the lubricator, 30 certain parts being shown in section.

Figure 2 is a side elevation of the same.

Figure 3 is a rear elevation partly in section.

Figure 4 is a transverse section on the 35 line 4-4 of Figures 1 and 2.

Figure 5 is a longitudinal sectional view on the line 5-5 of Figure 1.

Figure 6 is a detail cross sectional view 40 on an enlarged scale and on the line 6-6 of Figure 4.

Figure 7 is a detail perspective view of one of the lubricant supply stems.

Figure 8 is a detail perspective view of 45 the retaining and holding spring for such stem.

In the embodiment disclosed an elongated metal casing 9 is employed, the interior of which forms a lubricant reservoir 10. In 50 the top of the casing at the rear end is a

filling opening 11 for such reservoir, normally closed by a detachable plug 12.

Formed upon the opposite end is the nipple 13 of a main supply conduit 14, preferably formed integral with the casing and 55 extending longitudinally thereof within the chamber 10, but terminating short of the filling opening 11. This conduit is walled from the reservoir 10 and its bottom terminates short of the bottom of said reservoir, 60 so that lubricant placed in the reservoir can flow freely around the same. The inlet nipple 13 is interiorly threaded as indicated at 15, so that it can be coupled to a supply hose leading from any suitable source of 65 motive fluid under pressure. Extending from the opposite sides of the conduit 14 and in communication therewith are transversely disposed outlet branches 16, also preferably formed integral with the casing 70 and opening through opposite sides of the same, the ends being also in the form of internally threaded nipples 17, to which supply lines leading to the fluid operated tools can be connected. These branches as clearly 75 shown in Figures 4 and 5 are in the upper portion of the chamber 10 and terminate short of the bottom thereof, so that the oil or other lubricant can flow freely beneath them. 80

The branches 16 are transversely pierced through their tops and bottoms by aligned openings 18 and 19, the former being formed in the bottoms of upstanding nipples 20 formed on the top of the casing, said nipples 85 having enlarged chambers 21, the bottoms of which are beveled to provide seats 22. In the openings 18-19 are rotatably mounted stems 23 that thus pass across the passageways of the branches 16 and as shown, depend into the lower portion of the reservoir 10. The upper ends of these stems have enlarged beveled heads 24 that rest upon the beveled seats 22 and they are further provided just below said heads 24 with annular 90 grooves 25 that receive spring friction collars 26. These collars are expansible and frictionally bear against the walls of the upper openings 18 so as to hold the stems wherever placed and yet permit their rota- 100

tion. To this end the heads 24 are provided with sockets 27 to receive the nibs of a turning key. The stems are provided in their lower portions with longitudinal passageways 28 opening through their lower ends and terminating at their upper ends in transverse ports 29 that open through the opposite sides of the stem within the passageways of the branches 16. Above the ports 29 are right angularly set transverse ports 30, into which open the lower ends of longitudinal passageways 31 that extend upwardly through the upper ends of the stems and open into the chambers 21. From said chambers 21 passageways 32 lead downwardly and open into the upper portion of the reservoir 10.

When the manifold is coupled up by means of the nipple 13 with a main supply 20 hose and two or more of the branches (any unused branches being plugged) are connected to motive fluid operated instruments, such as a plurality of rock drills, it will be evident that the stems passing through the 25 branches which are in active use, will independently supply lubricant from the common reservoir to said branches and that this lubricant will be vaporized and carried to the tools. If a maximum supply is desired 30 to one of the tools, the stem is set so that the port 29 lies longitudinally of the branch in which case it is found that a maximum supply of oil will be carried up the passageway 28 and delivered into the air or other 35 motive fluid stream. If, however, one or more of the tools need a less amount, the stem in the branch of the manifold to which that tool is connected, can be turned with the port 29 more nearly to a right angular 40 position to the passageway through the branch and the supply of oil thereby cut down as desired.

With this structure therefore a common 45 lubricator is provided that can be made to properly serve a plurality of tools.

From the foregoing, it is thought that the construction, operation and many advantages of the herein described invention will be apparent to those skilled in the art with- 50 out further description and it will be understood that various changes in the size, shape, proportion and minor details of construction may be resorted to without departing from the spirit or sacrificing any of the advan- 55 tages of the invention.

What I claim is:

1. In a lubricator, the combination with a casing having a lubricant reservoir, of a motive fluid supply manifold associated with 60 the reservoir and comprising a main supply conduit having a plurality of branches for connection with different fluid operated instruments, and stems extending directly to the reservoir at different points and having 65 passageways for directing lubricant from

the reservoir to the branches of the manifold.

2. In a lubricator, the combination with a casing having a chamber constituting a lubricant reservoir, of a manifold for the transmission of motive fluid formed in but walled from the reservoir and including a conduit having a plurality of branches extending along the top of the reservoir, and independent stems mounted transversely of the branches and extending directly into the reservoir at different points, said stems having passageways for conducting lubricant from the lower portion of the reservoir into the branches. 75

3. In a lubricator, the combination with a casing having a chamber constituting a lubricant reservoir, of a manifold for the transmission of motive fluid formed in but walled from the reservoir and including a conduit having a plurality of branches located over the reservoir, independent stems adjustably mounted transversely of the branches and depending into the lower portion of the reservoir, said stems having passageways for conducting lubricant from the lower portion of the reservoir into the branches, and means accessible from the exterior of the casing and branches for adjusting the stems. 80

4. In a lubricator, the combination with a casing having an internal chamber forming a lubricant reservoir, of a manifold formed in the upper portion of the casing and including a main supply conduit and oppositely extending branches leading therefrom and opening at opposite sides of the casing, said branches extending over different portions of the reservoir and being transversely pierced, and stems mounted on the transverse perforations and depending below the branches into the lower portion of the reservoir at different points, said stems having passageways for the lubricant opening into the lower portion of the reservoir and into the branch passageways, the stems being accessible at the top of the casing. 100

5. In a lubricator, the combination with a casing, of a manifold for the transmission of motive fluid formed in the top of the casing and including a supply conduit having a plurality of outlet branches, said casing having a chamber beneath the manifold and forming a lubricant reservoir that is common to and beneath the branches, and stems depending from the branches into the portion of the reservoir therebeneath and at different points therein, said stems having passageways for conducting the lubricant from the reservoir into the respective branches of the manifold. 115

In testimony whereof, I affix my signature.

GUSTAV C. PEARSON.
